UNITED STATES PATENT OFFICE.

FRANK A. MAGEE, OF WENHAM, MASSACHUSETTS, ASSIGNOR TO THE MAGEE
FURNACE COMPANY, OF BOSTON, MASSACHUSETTS.

DESIGN FOR A STOVE.

SPECIFICATION forming part of Design No. 31,512, dated September 12, 1899.

Application filed August 18, 1899. Serial No. 727,705. Term of patent 14 years.

To all whom it may concern:

Be it known that I, FRANK A. MAGEE, a citizen of the United States, residing at Wenham, in the county of Essex and State of Massachusetts, have invented and produced a new and original Design for Stoves or Ranges, of which the following is a specification, reference being had to the accompanying drawing, forming a part thereof.

10 The figure is a view in perspective of the stove or range.

The salient features of the design comprise the stove as a whole and the essential parts of the stove which go to provide it with its distinctive features and which comprise the base, the oven-door, the ash-pit door, the plate below the ash-pit door, the side shelf, and the elevated shelves and smoke-pipe case.

20 The base A has a central shell-like figure a , inclosed by border-lines. Upon each side are two plain panels $a' a''$, with border-lines above and below, the lower border-lines being curved, as represented.

25 The legs B are of an Eastlake character, with a leaf at the upper corner of each and

sprays of leaves on each side of the main leaf, dropping downward.

The oven-door C has a name-plate space c , and each corner has a combined scroll leaf 30 and shell design c' . The door D is plain upon its sides and has a relatively large shell design d . The plate E below the door D has a scroll e , extending downwardly and ending in a leaf e' , the points of which extend upward. The side plate F has an open-work pattern of the character represented.

The upper shelves G G' are rectangular in shape and each is mounted upon an open-work of a combined scroll and leaf pattern g , 40 each of which emanates from the box or casting H, which is outwardly rounded and upon which are sprays of the scroll-and-leaf design.

Having thus described the design and its essential parts, what I claim as new, and desire to secure by Letters Patent, is—

The design for a stove as herein shown and described.

FRANK A. MAGEE.
